(57) **CLAIM**

The ornamental design for an applicator with blade, as shown and described.

DESCRIPTION

FIG. 1 is a bottom perspective view of the applicator portion of the applicator and blade, embodying our new design; FIG. 2 is a bottom view thereof; FIG. 3 is a top view thereof; FIG. 4 is a left view thereof; FIG. 5 is a right view thereof; FIG. 6 is a rear view thereof; FIG. 7 is a front view thereof; FIG. 8 is a bottom perspective view of the blade portion of the applicator and blade; FIG. 9 is a bottom view thereof; FIG. 10 is a top view thereof; FIG. 11 is a left view thereof; FIG. 12 is a right view thereof; FIG. 13 is a rear view thereof; FIG. 14 is a front view thereof; FIG. 15 is a bottom perspective view of the applicator and blade, wherein the blade is not coupled to the applicator; and, FIG. 16 is a bottom perspective view of the applicator and blade, wherein the blade is coupled to the applicator. All broken lines represent unclaimed features of the article to which the design is applied.

1 Claim, 8 Drawing Sheets
